Middletown, Ohio, assignors, by mesne assignments,
to Continental Can Company, Inc., New
York, N. Y., a corporation of New York

Application February 16, 1940, Serial No. 319,200

14 Claims. (Cl. 93—81)

This invention relates to container manufacture and more particularly to the formation of tubular bodies for containers and the like.

It is a principal object of the invention to provide in the manufacture of tubular container bodies a simple, effective and inexpensive process for applying to a web of suitable material as fed from a jumbo roll a coating of surface protective material in predetermined spaced areas thereon followed by the cutting of the web into lengths suitable for forming the container bodies and in which the application of each of the coatings is coordinated with the cutting operation in predetermined timed relationship so that the coating is accurately spotted in desired location.

It is a further object to provide a continuous process in which a protective surfacing is present upon and substantially restricted to that part of the tubular body which is exposed upon the interior thereof by effecting application of spaced surfacings to a web of paper material and cutting the web in predetermined timed relationship with each surfacing application so that such surfacing will be accurately located in its desired relationship upon winding into tubular form.

It is also an object to provide a machine of the character described for forming tubular container bodies as a continuous operation by effecting the application of surfacing material in predetermined spaced areas to a web of paper as fed from a jumbo roll and cutting the web in coordinated relation with the application of the surfacings to provide for locating the surfaced areas upon that part of the web which will be upon the inner exposed surface of the formed tubular container.

It is a still further object to provide a simple and effective machine having provision for applying a surfacing material in predetermined spaced areas upon a web of paper and for feeding and cutting the coated web, all actuated by interconnected driving mechanism so regulated and coordinated that such coated areas are located in predetermined desired position to be effective in the proper location and to afford the desired protection to the formed container body.

Other objects and advantages will be apparent from the following description, the accompanying drawings, and the appended claims.

In the drawings—

Fig. 1 is a schematic view of an apparatus suitable for carrying out the present invention in conjunction with the winding and formation

of the lengths of paper into the form of tubular container bodies;

Fig. 2 is a view on a somewhat larger scale of a portion of the mechanism shown in Fig. 1 which provides for the application of the surfacing material in spaced areas to the traveling web of paper; and

Fig. 3 is a schematic view showing an arrangement for effecting the multiple application of 10 continuous or discontinuous coatings.

In the formation of tubular container bodies and the like, and particularly with reference to bodies having a surfacing material thereon to provide protection for the container, substantial economies may be effected if the surfacing which is provided for protecting the exposed interior of the container may be substantially restricted thereto. In the manufacture of convolute wound tubular bodies, this may be accomplished by forming the material from which the container is wound with the surfacing located in spaced areas thereon, and by then winding the material in such manner that the surfacing is made available upon the inner exposed surface of the container, leaving the remainder thereof substantially free of surfacing. Economy is effected in this way by reason of the fact that in the case for example of a convolute wound body comprising three or more plies, the surfacing material is required to cover only that part forming the interior exposed surface, with a small amount of underlap if desired, so that it need cover only approximately one-third of the total surface of the sheet of material. And further since the surfacing material is not present throughout the entire wound body, such body may be adhesively secured upon itself relatively simply and through the use of inexpensive adhesives. Where formed of paper material, and with the overlying paper surfaces in contact with each other the requirements as to character and quality of the adhesive to secure the surfaces together is relatively quite simple as compared with the necessity for adhesively securing together plies having a protective surfacing layer thereon of greaseproof or moistureproof material for example.

In the Fisher et al. Patent No. 2,163,316, assigned to the same assignee as this application, there is disclosed a process by means of which discontinuous coatings are applied to a web of paper to provide protection upon the interior of the formed tubular bodies. In the particular arrangement therein disclosed, concurrently with the application of the coatings, indexing mark-

ings such as notches are formed in the margin of the web, the web being either wound into a roll for subsequent use, or advanced without intermediate winding to the forming operation for forming the same into container bodies. In the forming operation suitable mechanism is provided for sensing the location of the indexing markings, and the web is then cut into suitable lengths with relation to the coated areas thereon. In this arrangement therefore the web itself is utilized in securing properly coordinated operation, and there is no necessary coordination either as to time or spatial relation between the mechanism which applies the surfacings and that which effects the cutting of the web.

In accordance with the present invention the entire series of operations of applying the surfacing material in spaced areas to the web as fed from a jumbo roll, the feeding and cutting thereof into lengths is effected simply and efficiently upon a single machine as a continuous definitely coordinated operation. The surfacing applying mechanism and the cutting mechanism are located in predetermined spaced relation to each other upon the machine, and are correlated to operate in predetermined time relation through suitable interconnected drive mechanism; in this way the coated web is cut into lengths suitable for winding and having the surfaced areas thereof in such predetermined relation to the sheet that each of them will be present to perform its protective purpose when the web is wound into tubular container form. Being carried out in this manner continuously and upon a single machine, the necessity for indexing the location of the surfaced areas upon the sheet itself or for sensing their position is dispensed with, and the entire operation is simplified, and made more certain and accurate. With the several operations being carried out concurrently and by interconnected mechanisms, it is not possible for the operations to become out of step with each other, and any desired correlation may be secured and accurately maintained by suitably arranging the driving connections. Also it is not possible for errors in alignment, length of web or the like to accumulate and any such errors arising for example from change in length of the web when wet with a coating solution or from other causes are restricted at most to those occurring within a single blank length and as such are relatively quite simple to compensate for and correct.

When such mechanism surfacing applications may be effected of a character suitable to develop desired protective characteristics, such as resistance to the penetration or transudation of various solvents, moisture, grease, and the like. Likewise through such operations the sheet either with or without a preliminary coating may be treated to provide surfacings thereon consisting of one or more applications of either a continuous character or arranged in predetermined spaced relation to each other to locate the surfaced area upon or within a desired portion of the formed container.

Referring to the drawings which disclose a preferred embodiment of the invention a jumbo roll of paper is shown at 10 from which a traveling web 11 is led, passing around fixed idler roll 12 and around a movable contact roll 13. The fixed position of idler roll 12 permits the motion of movable contact roll 13 without substantially changing tension in the traveling web 11. Roll 13 is pivotally mounted as shown at 14 on an arm 15 supported from bracket 16 and which in

turn is mounted upon the frame of the machine 17. In order to provide for pivotal swinging movement of contact roller 13, a connecting link 20 is attached to the end of arm 15 and connects with a lever 21 pivotally mounted at 22 and having a forwardly projecting arm 23 carrying a cam follower 24. The cam follower 24 is moved in accordance with the groove formed in the face of rotatable cam cylinder 25. Such cam is constantly driven by suitable drive means such as a common source of motive power 26, which through sprocket chain 27 drives shaft 28, this in turn being arranged to operate cam 25 in definitely coordinated relation through sprocket chain 29.

The application of the surfacing material is effected by means of a pair of rolls 30, 31. These rolls are mounted in horizontal alignment, roll 31 preferably being arranged to be moved longitudinally toward and away from the roll 30 and may be adjusted in predetermined accurate spacing under the manual control of a regulating device 32.

A positive drive mechanism is provided for actuating rolls 30, 31 comprising a sprocket chain 34, suitably driven from the shaft of cam 25, and driving into a change speed device indicated diagrammatically at 35 which provides for operating a driven sprocket chain 36 at suitably variable rates of speed. Chain 36 passes over sprockets 37 and 38, carried respectively by rolls 30 and 31, in the direction to provide for driving both said rolls in the same angular direction, thereby providing for opposite movement of the surfaces of the rolls at their nip. Preferably as shown the sprocket wheel 37 is of smaller diameter than sprocket wheel 38 and hence roll 30 is caused to rotate at a higher speed, approximately twice the peripheral speed of roll 31. The peripheral speed of roll 30, from which the coating is transferred to the moving web may be regulated from a speed less than to a speed greater than that of the web, a higher speed of the transfer roll resulting in the application of a thinner coating and vice versa.

Under the control of cam 25, the contact roll 13 is periodically moved to establish a coating transferring relationship between web 11 and roll 30, such period of transfer preferably being arranged to continue for approximately one-third of the complete cycle so that coating will be applied to only a predetermined portion of the entire length of the blanks.

The material to be applied as the surfacing material is introduced continuously at a regulated rate of flow above the nip of the rolls by suitable means indicated at 39. The material accumulates upon and distributes itself uniformly across the nip and excess, if any, is discharged over the ends of the rolls where it falls upon a collecting trough 40 and is withdrawn for reuse through conduit 42. Ordinarily dams 41 are provided at each end of the nip to return the material in the nip. A stationary scraper or doctor member 43 tends to prevent material from being carried around the surface of roll 31, and another similar member 44 is provided to remove material therefrom and discharge it into trough 40 so that the surface of roll 31 as it enters the nip is substantially smooth and clean, and hence is in condition to regulate the quantity of material which is allowed to pass through the nip on the surface of the transfer roll 30.

Certain of the materials desired to be utilized in the surfacing or coating operation have volatile

characteristics, and in order to limit and reduce the escape of such volatile constituents and to provide for maintaining a uniform and homogeneous surfacing film upon the transfer roll, a casing 45 is provided which substantially completely encloses rolls 30 and 31. An opening 46 is formed in the casing adjacent one side of roll 30, and it is through this opening that the contact roll 13 effects the bringing of the web of paper into transferring contact with the roll 30 in properly timed relation to provide for applying surfacing material thereto as desired. It will be clear that the time in the cycle of feeding during which the web is thus brought into transferring contact may be regulated by varying the position of cam 25 upon its driving shaft, and the length of time during which the web is maintained in transferring relation may likewise be varied by suitable selection of the contour of the cam and the length of rise thereof.

It will thus be seen that material introduced through pipe 39 is caused to collect in a pool at the nip of the coating rolls and is formed into a film of regulated thickness upon the surface of transfer roll 30, being carried around on such surface and at the proper time and for the proper duration being brought into transferring relation with the web, the web being carried across the surface of roll 30 in a direction opposite to the direction of travel thereof as indicated by the arrows in Fig. 2, so that such regulated film is uniformly wiped from the surface of roll 30 and transferred to the web as a smooth homogeneous film of proper weight. By suitably regulating the variable speed device 35 to provide an increased or decreased speed of operation of the coating rolls more or less coating respectively will be transferred to the web. Similarly increasing the spacing between rolls 30 and 31 will provide for the application of a heavier regulated film and the transfer of such film to the web.

The surfacing material applied by means of the application rolls 30, 31 may be selected to provide suitable characteristics and to provide protection of the character desired in the final wound container. Also the coating may be applied in one or in a plurality of stages through the provision of additional coating applying means similar to that described above and operating in predetermined correlated relation with the web and with each other. Also the coating may be applied directly to the web of paper as initially produced, or to a web which has been provided with a lower or base coating of suitable type. Thus as shown diagrammatically in Fig. 3, the web 100 passes through a first coating applying means 101 where it may receive an extended or if desired a continuous surface coating following which it is dried or conditioned at 102, and fed to a second coating applying unit 103 which is located in definite and predetermined spaced relation with respect to the first such unit. At the second unit a further coating application is effected, in predetermined overlying relation to the first coating application, and also in predetermined relation to the length of material to be cut from the web for winding into tubular container form. The web may be then additionally treated at 104, and if desired subjected to a still further coating application at 105. Following treatment in the conditioner 106, the web is fed forwardly the proper distance and cut into lengths by knife means 107, and is then wound into the desired tubular container form upon the winding mandrel assembly 108, 75

the construction and operation of all of these parts being similar to that previously described herein. The several coating, cutting, and winding means are located in proper predetermined spaced relation and are coordinated in proper timed relation through a coordinating drive mechanism 109 to provide for cutting and winding the lengths with the several coated areas thereon occupying the proper desired positions 10 within the formed tubular body.

In the manufacture of tubular container bodies adapted for the packaging of oil, grease, and the like, it is found desirable to utilize a composite coating comprising a lower coating layer having high flexibility and an overlying layer having high greaseproofness. Reference is made to Swan Patents 1,957,368, 1,957,369 and 2,039,361 assigned to the same assignee as this application, such patents showing the provision of composite surfacings of this character. In the practicing of the present invention the web as supplied from the jumbo roll may have a continuous coating of a previously applied suitable base coat as disclosed in said Swan patents, consisting for example of the following parts by weight:

Casein	321
Rubber latex—38% solids	1100
26° Baumé ammonia	38
40% formaldehyde	35
Glycerine	80
Water to make	gallons 500

The overlying top coat, which is to be applied in predetermined spaced areas, may comprise a lacquer and have a composition as described in said patents. The following is an example of a satisfactory cellulose ester material which may be utilized with plasticizers and applied from solution by means of rolls 30, 31:

Nitrocellulose of 5 second viscosity, wet	
with 30% alcohol	16.7
Amberol resin 801	5.9
Tricresyl phosphate	7.5
Benzol	38.4
Alcohol	16
Ethyl acetate	15.5

Total (parts by weight with substantially 25% solids) 100.0

When a composition of this character is applied in the manner above described a highly satisfactory and uniform regulated film thereof may be formed and transferred to the web. Nitrocellulose of lower viscosity may be utilized in place of the above and likewise nitrocellulose having a viscosity substantially above 5 seconds may be successfully applied. Further the character and proportions of the solvents may be controlled to secure desired characteristics of drying, etc.

The invention also provides for the satisfactory utilization of aqueous emulsions, such for example as emulsions of nitrocellulose, various resins, bitumens, etc. Such emulsions are supplied to the press rolls 30, 31 and by them applied in predetermined spaced relation to the sheet in the manner above described. Such emulsion coatings may be applied to the untreated sheet, or if desired the sheet may be formed initially with a lower continuous coating which is adapted to resist and limit the penetration of the emulsion into the body of the sheet; a suitable lower coating of this character has been found to be a starch, preferably one of the modified soluble

starches which readily gels in water, or similar coating. As an example of an emulsion which produces highly satisfactory results as forming a clear coating film of plasticized nitrocellulose upon the sheet, and making a highly satisfactory greaseproof interior surfacing thereon, the following is given, the parts being by weight:

5 second nitrocellulose wet with butyl alcohol (30%)	59.5
Amberol resin 801	29.3
Baker's #15 castor oil	24.0
Tricresyl phosphate	16.0
Butyl acetate	93.0
Toluol	93.0
Water	104.0
Duponol M. E. (stabilizer)	1.0
Turkey red oil (emulsifying agent)	.5
Solids content 26.4%.	

If desired pigments may be added to produce desired color and appearance upon the formed film. For example by adding carbon black, a film is provided having a deep black color and a high gloss, the color being desirable as tending to resist deterioration of the coating under the action of light. Similarly the use of a white mineral filler such as titanium dioxide provides the coating with a brilliant white color.

In addition to the use of nitrocellulose as above described, emulsions may be prepared consisting of vinyl resins included in the lacquer phase either with or without nitrocellulose, such resins providing a highly pure and substantially tasteless and odorless material adapted for use in connection with food containers and the like. An example of the use of such resin follows:

Vinylite resin (Gelva 15)	1000
Toluol	740
Tricresyl phosphate	100
 Total parts by weight	1840

The water phase comprises:

Water	613.
Turkey red oil	6.13
Duponol M. E.	3.1
 Total parts by weight	622.2

The emulsion comprises 1840 parts of the resin solution with the 622.2 parts of water solution.

Also certain thermoplastic materials such as waxes, resins, bitumens, etc. may be applied in a melted condition, rolls 30, 31 and other associated parts being heated as by internal steam pressure, to maintain the surfacing material in a flowable and workable condition.

It is important in the formation of the surfaced areas that the freshly coated films be protected during the period of drying and setting against premature contact with any surface which might cause injury thereto. Inasmuch as the web continues its forward travel through the machine after the application of the coating thereto, to be thereafter wound into the form of tubular container bodies, it is important to provide for the drying and setting of such coating materials before damage can occur thereto. For this purpose the web after receiving the coating thereon passes into a treating chamber 50 in which suitable means are provided for treating the surface of the web to dry and set the coating. A satisfactory means for this purpose consists in the use of infra-red lamps, arranged in a bank below the web and directing infra-red rays upon

the coated surface to penetrate into the body thereof and to cause rapid and thorough drying. Suitable ventilating means may likewise be employed in conjunction therewith. While the use of such light sources is desired in view of their prompt and effective action, other suitable means may likewise be employed to produce a setting of the film, as by the use of heated air, radiated heat, etc., to render the coated web substantial non-sticky and non-adherent to the feed rolls. In the case of the application of thermoplastic surfacings, suitable cooling or refrigerating means may be supplied in chamber 50 for causing rapid setting of such coating.

After leaving the chamber 50, the web passes between feed rolls 55 which are arranged to draw the web through the coating applying means and through the treating chamber, the coating having been sufficiently dried and set at the time it is contacted by the feed rolls 55 so that no damage is occasioned thereto.

The web then travels through an additional feed roll pair 58 and into position on the table 59 where it is subject to shearing action by the cutting means 60. Cutting means 60 is actuated by means of connecting rod 61 from a crank arm 62 suitably driven from a cam 63 mounted upon the shaft 28. Shaft 28 is arranged with suitable mechanism indicated diagrammatically at 64 for driving feed rolls 58 intermittently, providing for feeding a predetermined length of web, and then stopping the web during the actuation of cut-off means 60. Thus the operation of the shearing knife 60 is coordinated with the feeding operation in such manner that the shearing of the web in the desired lengths takes place during periods of stoppage of the feed. Suitable drive means for this purpose are described fully in Scusa et al. Patent No. 2,163,318, assigned to the same assignee as this application. Sprocket chain 65 provides for driving feed rolls 55 at the same speed and in the same cycle of intermittent movement as rolls 58.

The shearing knife 60 is located in predetermined spaced relation with respect to the coating applying means and the cutting operation takes place in such predetermined time relation to the application of the coating that the web is definitely and accurately cut along substantially the leading edge of the coated portion thereof. Furthermore the parts are so coordinated that the operation of transferring the coating to the web takes place during the forward feeding movement, and not during a period of stoppage of feeding; hence at each period in the cycle when the feeding operation is stopped, the contact roll 13 has moved to position to space the web from the transfer roll 30, thereby avoiding application of an excess of coating material to the web at any time. Such material as remains on the surface of roll 30 during the time that it is out of contact with the web is merely carried back into the pool above the nip of rolls 30, 31.

Following the cutting of the web, the cut length is drawn forwardly under a guide member 70 by means of which it is kept flat, under the action of feed roll pairs 71, 72, and if desired passed under spaced slitting knives 73 which slit the web transversely into a plurality of container blanks each adapted to be wound into the form of a container body. These series of blanks are then supplied to the grippers 75 on a winding mandrel 76, which is arranged in a suitable assembly frame 77 to be rotated through a series of operative positions. In the winding position

the mandrel 76 rotates to wind the web upon itself with the coated surface of the web upon the interior, the length of the coated portion being sufficient to overlie the entire interior surface of the body and preferably an additional portion to provide an underlap. During the winding operation adhesive may be applied thereto from a bath 78 in which there rotates a pick-up roll 79 having contact with a movable transfer roll 80 which in turn is selectively brought into engagement with the outer surface of the web at a proper point in the winding operation. Since in the preferred position the web is wound so that the special surfacing is exposed upon and substantially confined to the interior of the formed tubular body and the adhesive is applied to the external surface of the web, the adhesive is almost entirely located on and between surfaces of the web which are free of such coating. Consequently such adhesive may be of relatively inexpensive material and may be applied as desired to be effective upon the entire surface of the web being wound, or only upon a portion thereof. Likewise it may be continued around the outer surface of the wound container to serve as a means for adhesively securing a label or the like thereto.

Following the winding step the mandrel assembly 77 is rotated to carry the mandrels successively through the series of operating stages in which the formation of the container body is carried to completion, the bodies being stripped in the final position as completely formed tubular container bodies having the protective surfacing material effective over their entire interior surface.

The invention provides a highly simple and effective arrangement for producing tubular container bodies from a traveling web of paper as fed from a jumbo roll, and having a surface coating applied thereto in such position as to be effective upon the entire interior surface to afford protection thereto, and substantially restricted thereto leaving the remainder of the bodies free of surfacing and such that they may be secured quickly and easily through the use of inexpensive adhesives. The operations are carried out in definitely correlated time and space relation with each other so that the coating is applied accurately and economically to a limited portion of the web, avoiding difficulties of securing register and assuring the uniform production in continuous operation of tubular bodies provided with effective and impervious inner surfacings.

While the process and apparatus herein described constitute preferred embodiments of the invention, it is to be understood that the invention is not limited to this precise process and apparatus, and that changes may be made therein without departing from the scope of the invention which is defined in the appended claims.

What is claimed is:

1. In a process for forming tubular bodies for containers and the like the steps which comprise periodically transferring to a traveling web of sheet material a surfacing material to provide for application thereof to said web in predetermined areas spaced from each other lengthwise of the web, feeding the web forwardly a predetermined distance and then stopping the feeding operation, cutting the web in predetermined coordinated time and space relation with the step of applying of the surfacing material to form the web into lengths suitable for winding into tubular

bodies with the surfacing material located at the leading end portion thereof to be effective upon the interior exposed surface of the container, and thereafter winding said lengths into the form of convolute wound tubular bodies with said surfaced area exposed upon the interior thereof.

2. In a process for forming tubular bodies for containers and the like the steps which comprise 10 periodically transferring to a traveling web of sheet material a surfacing material to provide for application thereof to said web in predetermined areas spaced from each other lengthwise of the web, feeding the web forwardly a predetermined distance and then stopping the feeding operation, and cutting the web during periods of stoppage thereof and in predetermined coordinated time and space relation with the step of applying of the surfacing material to form the web into lengths having the surfacing material located to be effective in a predetermined portion thereof, thereafter winding said lengths into the form of convolute wound tubular bodies with said surfaced area exposed upon the interior surface thereof, and applying adhesive to the overlying surfaces of said wound bodies to retain the same in wound form.

3. In a continuous process for forming tubular bodies for containers and the like having an inner protective surfacing thereon, the steps 30 which comprise periodically bringing a traveling web of sheet material into contact with a coating material and transferring such coating to the surface of the web to provide coated areas thereon in predetermined areas spaced from each other lengthwise of the web, intermittently feeding the web forwardly a predetermined distance and thereafter stopping the feeding operation of the web, controlling the feeding of the web in 35 relation to the applying of the coating to assure continuous feeding throughout the period of coating to provide a smooth and uniform coating thereon, cutting the web in coordinated time and space relation with the transferring operation to 40 form the web into lengths suitable for winding into the form of multi-wall tubular bodies with the surfacing material located in predetermined relation with respect to said cut length, and winding said cut lengths into tubular body form 45 with said coated areas located to be effective in predetermined relation to the overlying and exposed walls thereof.

4. In a continuous process for forming tubular bodies for containers and the like having a protective surfacing thereon, the steps which comprise 50 periodically bringing a traveling web of sheet material into contact with a coating material and transferring such coating to the surface of the web to provide coated areas thereon in predetermined spaced relation to each other lengthwise of the web, intermittently feeding the web forwardly a predetermined distance and thereafter stopping the feeding operation of the web, controlling the transferring of the coating 55 to effect such transfer only during periods of movement or during periods of feeding of the web, engaging the leading end of the web prior to cutting with a winding element, cutting the web during periods intermediate the operations of transferring coating to the web and during stoppage thereof in coordinated relation with the transferring operation to form the web into lengths suitable for winding into the form of tubular bodies with the surfacing material located to be effective in predetermined position

upon the walls of the wound body, and thereafter winding the cut lengths into convolute wound body form during the subsequent feeding operation.

5. In a continuous process for forming tubular bodies for containers and the like having an inner protective surfacing thereon, the steps which comprise periodically bringing a traveling web of paper into contact with a coating material and transferring such coating to the surface of the web to provide coated areas thereon in predetermined areas spaced from each other lengthwise of the web, subjecting the web to a conditioning treatment following said transfer to cause the setting of the coated areas, thereafter engaging the web to cause intermittent feeding thereof a predetermined distance forwardly, cutting the web during periods of stoppage and in predetermined coordinated relation with the applying of the coating to form the web into lengths suitable for winding into the form of tubular bodies with the surfacing material located to be effective upon the interior exposed surface of the container, thereafter winding said lengths into the form of convolute wound tubular bodies with said surfaced area exposed upon the interior surface thereof, and applying adhesive to the overlying surfaces of said wound bodies to retain the same in wound form.

6. In apparatus of the character described for continuous formation from a web of sheet material of tubular container bodies having a protective surfacing thereon, means for periodically applying a surfacing material to the traveling web to provide protective surfacing areas thereon spaced from each other lengthwise of the web, means for intermittently feeding said web with the spaced surfacing areas thereon forwardly for a predetermined distance, means providing for continuous operation of said feeding means during periods of applying surfacing material to the web, means located in predetermined spaced relation with respect to said applying means for cutting the web into lengths suitable for winding into the form of multi-wall tubular bodies with the surfacing material located to be effective in predetermined relation upon the walls of said container, means for actuating said cutting means during the time said web is stopped, and means for effecting complete winding of each of said cut lengths in a single continuous winding operation.

7. In apparatus of the character described for continuous formation from a web of sheet material of tubular container bodies having an inner protective surfacing thereon, means for periodically applying a surfacing material to the traveling web to provide protective surfacing areas thereon spaced from each other lengthwise of the web, means for intermittently feeding said web with the spaced surfacing areas thereon forwardly for a predetermined distance, means providing for continuous operation of said feeding means during periods of applying surfacing material to the web, means located in predetermined spaced relation with respect to said applying means for cutting the web into lengths with the surfacing material located to be effective in a predetermined portion thereof, means for winding said lengths into convolute wound tubular bodies with said surfaced area exposed upon the interior surface thereof, and means for applying adhesive to the overlying surfaces of said wound bodies to retain the same in wound form.

8. In apparatus of the character described for

continuous formation from a web of sheet material of tubular container bodies having protective surfacing thereon, means for applying a surfacing material to the traveling web of sheet material to provide protective surfacing areas thereon spaced from each other lengthwise of the web, means for intermittently feeding said web with the spaced surfacing material thereon forwardly for a predetermined distance, means located in predetermined spaced relation with respect to said applying means for cutting the web into lengths suitable for winding into the form of tubular bodies with the surfacing material located to be effective in predetermined relation upon the surface of the formed container body, winding means in predetermined spaced relation with respect to said cutting means for receiving the leading edge of said web prior to the cutting thereof, and means for rotating said winding means to complete the winding of each of said cut lengths as a single continuous operation.

9. In apparatus of the character described for continuous formation from a web of paper of tubular container bodies having an inner protective surfacing thereon, means for applying a surfacing material to the traveling web of paper to provide protective surfacing areas thereon spaced from each other lengthwise of the web, means for intermittently feeding said web with the spaced surfacing material thereon forwardly for a predetermined distance, means located in predetermined spaced relation with respect to said applying means for cutting the web into lengths suitable for winding into the form of tubular container bodies, interconnecting means for coordinating the action of said cutting means and said applying means to cause said means to operate in predetermined timed relation with each other to locate said surfacing material upon said length of paper in predetermined position thereon, and means located in predetermined spaced relation to said cutting means at approximately the distance of a length of said material for receiving the cut length and for winding said length into tubular form.

10. In apparatus for forming tubular bodies for containers and the like from a jumbo roll of paper, means for intermittently feeding a web of paper from said jumbo roll, coating applying rolls, means for continuously rotating said rolls, means for forming a regulated film of coating on said coating applying rolls, means for intermittently bringing the web of paper into coating transferring contact with said coating film during periods of feeding of said web to provide coated areas thereon spaced from each other lengthwise of the web, means for cutting the web of paper into lengths suitable for winding into the form of tubular bodies, a common drive means for operating said cutting means and said transferring means in predetermined relation to each other to effect the application of said coating to the web in predetermined relation thereto, means located in predetermined spaced relation to said cutting means for winding the cut lengths of said web, and means for coordinating said winding and feeding means to effect concurrent timed relation thereof.

11. In apparatus for forming tubular bodies for containers and the like having an inner protective surfacing thereon as a continuous operation from a jumbo roll of paper, coating applying rolls, means for driving said rolls, means for forming a regulated film of coating material on one of said coating applying rolls, means for

intermittently transferring said regulated film of coating to the web of paper to provide coated areas thereon spaced from each other lengthwise of the sheet, means for intermittently feeding the web of paper with the coating thereon a predetermined regulated distance, means located in predetermined spaced relation with respect to the coating means for cutting the web of paper into lengths suitable for winding into the form of tubular container bodies, means for driving said coating applying means and said cutting means in predetermined relation to each other to provide for cutting of the web substantially at the leading edge of the coated area to make said coating available for protective purposes upon the interior of the formed tubular bodies, and means for thereafter continuously winding said cut lengths into tubular container form with said coated areas located upon the interior exposed areas thereof.

12. In apparatus for forming tubular bodies for containers and the like having an inner protective surfacing thereon as a continuous operation from a jumbo roll of paper, coating applying rolls, means for driving said rolls, means for forming a regulated film of coating material on one of said coating applying rolls, means for periodically transferring said regulated film of coating to the web of paper to provide coated areas thereon spaced from each other lengthwise of the sheet, means for conditioning the applied coating and maintaining the sheet free of contact until said coating has become substantially set, means for thereafter intermittently feeding the web of paper with the coating thereon a predetermined regulated distance, means located in predetermined spaced relation with respect to the coating means for cutting the web of paper into lengths suitable for winding into the form of tubular container bodies, means for driving said coating applying means and said cutting means in predetermined relation to each other to provide for cutting of the web substantially at the leading edge of the coated area to make said coating available for protective purposes upon the interior of the formed tubular bodies, and means for thereafter continuously winding said cut lengths into tubular container form with said coated areas located upon the interior exposed areas thereof.

13. In apparatus for forming tubular bodies for containers and the like having an inner protective surfacing thereon as a continuous operation from a jumbo roll of paper, coating applying rolls, means for driving said rolls, means for forming a regulated film of coating material on one of said coating applying rolls, means for

periodically transferring said regulated film of coating to the web of paper to provide coated areas thereon spaced from each other lengthwise of the sheet, means for intermittently feeding the web of paper with the coating thereon a predetermined distance forwardly and for then stopping the feeding operation, means for cutting the web of paper during periods of stoppage of feeding into lengths suitable for winding into the form of tubular container bodies, a common drive means for coordinating the operation of said periodic means and said cutting means to provide for cutting intermediate periods of coating and in such relation as to locate the coated areas in position to be exposed upon the interior surface of the formed container bodies, winding means located at a predetermined distance from the cutting means of approximately the distance of a length of said material, and means for coordinating the operation of said feeding means and said winding means to provide for winding said cut lengths into tubular form during periods of feeding said web.

14. In apparatus for forming tubular bodies for containers and the like having an inner protective surfacing thereon as a continuous operation from a jumbo roll of paper, coating applying rolls, means for driving said rolls continuously, means for forming a regulated film of coating material on one of said coating applying rolls, a movable contact roll over which the web passes, means for periodically moving said contact roll and said web to bring the web during periods of feeding movement thereof into coating transferring relation with said coating applying rolls to provide coated areas thereon spaced from each other lengthwise of the sheet, means for intermittently feeding the web of paper with the coating thereon a predetermined distance forwardly and for then stopping the feeding operation, means for cutting the web of paper during periods of stoppage of feeding into lengths suitable for winding into the form of tubular container bodies, drive means for coordinating the operation of said periodic means and said cutting means to provide for cutting intermediate periods of coating and in such relation as to locate the coated areas in predetermined position thereon, winding means for receiving said cut lengths and winding said lengths into tubular form, and means for coordinating the operation of said winding means with said feeding and cutting means to provide for completing a winding operation during the feeding of the subsequent length of said web.
